UNITED STATES PATENT OFFICE.

EDWARD R. AMMON, OF READING, PENNSYLVANIA.

HOSIERY-INSPECTING DEVICE.

Application filed July 11, 1927. Serial No. 204,713.

The present invention relates to an improvement in hosiery inspecting devices. In some respects, it applies more particularly to apparatus for inspecting so-called seamless hosiery as distinguished from full fashioned hosiery. In other respects, the improvements are applicable to apparatus for inspecting either kind of hosiery. One object has been to provide a seamless hosiery inspecting form 5 of such shape and proportions that the stocking to be inspected may readily be drawn into inspecting position with the threads normally extended but not stretched for general inspection, the form being further provided with 10 extensible means for stretching toe portions of the stocking. In well known forms of seamless hose, the toe portion includes short knitted seams, the stitches thereof being referred to as gore stitches and looped seams 15 made by looping stitches which extend to the ends of the knitted seams. Another object of my invention is to provide means for effectively stretching said gore and looping stitches and particularly those known as corner stitches and located at the point where the 20 gore stitches and looping stitches meet. My improved construction also provides apparatus which may be operated in such a manner that the operator's hands will be left free 25 to draw on and pull off the stockings to be inspected. In some forms, rotation of the stocking holding form is accomplished by a 30 foot operated device so that the operator is relieved of the labor of turning or rotating the form. Other advantages and benefits will 35 be apparent from a consideration of the following description of a preferred form of my invention taken in connection with the accompanying drawings in which

40 Figure 1 is a side elevation;

Figure 2, a central longitudinal section enlarged to illustrate details of the form supporting and brake mechanism;

Figure 3, an enlarged rear end view;

45 Figure 4, a central longitudinal section of the forward end of a preferred embodiment illustrating the extensible members or fingers for expanding or stretching the gore stitches and looper stitches;

50 Figure 5, a fragmentary side view of an

end portion showing the extensible gore and looper stitch expanding fingers in extended position;

Figure 6, a transverse section on the line 6—6 of Figure 4;

55 Figure 7, a fragmentary side view further illustrating the shape of a preferred embodiment of my seamless stocking inspecting form;

Figure 8, a side view of a modification 60 showing foot operated means for rotating the form;

Figure 9, a side view of a further modification showing hand operated means for rotating the form and simultaneously advancing 65 and retracting the finger extending devices, the parts being shown in the relative positions occupied by them when the fingers are extended;

Figure 10, a fragmentary view thereof 70 illustrating the relative position of the parts when the fingers are retracted; and

Figure 11, a detail in transverse section on the line 11—11 of Figure 8.

In producing an apparatus for satisfactorily inspecting seamless hosiery, I have found that the most effective results are obtained in using a form having certain dimensions, proportions and terminal contours. As indicated in the drawings, the main or body portion of the form is substantially an elongated truncated cone and is provided at its forward end with an attenuated nose or wedge-shaped portion. In a commercial form for average size ladies', men's and larger size children's hosiery, the truncated cone portion is 29 inches long with a base diameter of $3\frac{5}{8}$ inches and an end diameter of $2\frac{5}{8}$ inches. The wedge-shaped end or projection extends about $1\frac{1}{2}$ inches beyond the narrower end of the truncated cone. The nose is formed with opposed flat faces arranged at an angle preferably of between 50 and 60 degrees and converging toward a rounded end portion of cylindrical contour forming part of a cylinder having a diameter of $\frac{5}{8}$ of an inch. As indicated in Figures 4 and 5, it will be noted that the extreme end of the nose is also slightly attenuated in the axis normal to the axis passing through the faces of the wedge hereinabove 100

referred to. The faces marking the end surfaces of the extreme attenuated portion are substantially $\frac{1}{2}$ inch long and are pitched at such an angle that the extreme forward edge 5 of each is $\frac{3}{16}$ of an inch nearer the central longitudinal axis of the form than an extension of the normal conical surface would be at the same distance from the base.

As indicated in Figures 4, 5 and 7 of the 10 drawings, the base 1 is of frusto-conical shape and is provided with a tip 100 consisting of a separate member having a threaded base and formed with converging flattened end surfaces 2 merging into a rounded edge 3. 15 Between said flattened surfaces 2 are minor converging surfaces defining corners 4 formed by intersection of the edge and lateral surfaces of the end or tip 100. Where a form as 1 is hollow, it is conveniently mounted on 20 a bracket 5 by suitable connecting means disposed inside the form. As indicated in Figure 2, an annular flange 6 inside the base of the form 1 supports a ball retainer 7. An axle 8 is secured to the bracket 5 and is provided 25 with ball engaging cones 9 cooperating with ball bearings 10 interposed between said cones and interior surfaces of retainer 7. It will be clear from the foregoing that the form 1 may readily be rotated around the 30 axle 8 which is preferably hollow for a purpose hereinafter to be explained.

The form is provided with extensible means for stretching the toe portion and particularly the gore and looper stitches thereof in 35 seamless hosiery, said means being in part carried by the tip 100. For this purpose, fingers 11 are formed on levers 12 pivotally mounted at 13 on interiorly disposed brackets 14 secured to said tip 100 and movable into 40 operative position when the tip is screwed into operative relation on the form 1. Springs as 15 are interposed between the levers 12 and interior portions of the casing or form to retain the fingers normally in retracted position. 45 The rod 17 having a wedge 16 at its forward or inner end extends longitudinally through the hollow shaft 8 and is provided at its outer end with a flanged collar 20 which cooperates with suitable means for thrusting 50 the rod forward and returning it to its rearward position. This motion of the rod or other finger extending instrumentalities may be effected in any desired manner either automatically upon rotation of the form or by 55 foot or hand actuated means. As indicated in Figure 1, a yoke 21 engages the collar 20, said yoke being secured to and movable with a link 22 pivotally secured at 23 to a bell crank 60 lever 24 pivotally mounted at 25. By deflecting the free end of bell crank lever 24 the rod 17 is moved forwardly thus extending the fingers 11 to the position indicated in Figure 5. In some cases it may be desirable to provide means for positively arresting rotation 65 of form 1, for example, so that a stocking may

be more readily drawn into operative position thereon. For such purposes, a brake shoe 26 is mounted on a shaft 27 journaled in the bracket 5. A lever 28 is secured to the outer end of shaft 27 and positioned with its free end engaging a lever 29 secured to a shaft 30 which is rotated by a lever 31 to the outer end of which is secured a link 32 having its lower end pivotally connected to a foot mechanism or treadle 33.

In the modification illustrated in Figure 8, it is contemplated that rotation of the form will be effected by a foot operated device instead of by manual rotation. For this purpose, the form 1 is mounted in any suitable manner as in a bearing of a bracket 34, said form 1 having a shaft 35 to the outer end of which is secured a gear meshing with a pinion 27 at the end of a shaft 38. A drum 39 is rotatably mounted on the shaft 38 and provided with a strap 40, the free end of which is secured to a treadle 41. As indicated in Figure 11, a recess 42 inside of cylinder 39 accommodates a ball bearing 43 and a spring 44 normally pressing said bearing toward and into engagement with shaft 38. In operation, when the strap 40 is moved downwardly in the direction of the arrow, Figure 11, the ball bearing 43 wedges between shaft 38 and the opposed surface of the recess 42, thus causing shaft 38 to rotate in a counterclockwise direction. As indicated in Figure 8, a torsion spring 45 has one end secured to the inner end of a hub 46 of drum 39, the other end being secured inside a housing 47 which also provides a bearing for said hub 46. In operation, when the treadle 41 is operated downwardly the shaft 38 advances and torsion spring 45 is simultaneously wound up. When pressure is removed from the treadle 41 drum 39 is free to return in a clockwise direction relatively to shaft 38 and is so moved by operation of spring 45.

In the modification shown in Figure 9, means are provided for rotating the form and simultaneously actuating finger extending instrumentalities. As indicated in said figure, form 1 is rotatably supported on a bracket 48 and is provided with a gear 49 engaging a pinion 50 secured to a shaft 51. A beveled gear 52 on said shaft 51 meshes with another beveled gear 53 mounted on a stud shaft 54 which is rotated by means of a crank or hand wheel 55. The bracket 48 also carries the cam 56 cooperating with another cam 57 supported on a bracket 58. A longitudinally extending rod 59 rotates with the form 1 but slides longitudinally with respect thereto and may be provided at its forward end with a wedge or other suitable device such as that shown in Figures 4 and 5 cooperating with extensible fingers or other suitable stretching means, said to and fro movement of rod 59 being accomplished by means of cams 56 and 57 cooperating with a cam fol-

lower 60 mounted at the end of an extension 61 on rod 59.

In the drawings hereinabove referred to, I have illustrated my invention in an embodiment employing my improved and preferred type of form or base. It is contemplated that the same or equivalent stocking stretching and form actuating or controlling instrumentalities may be incorporated in or used in connection with forms or bases of different cross sectional contour or other characteristics to effect a similar or equivalent result.

I claim as my invention:

1. A hosiery inspecting device comprising a form having an elongated body portion of substantially circular cross sectional contour and a terminal portion having opposed flat surfaces in angular relation to each other and converging to a narrow wedge-shaped end presenting a substantially straight edge normal to the central longitudinal axis of the body portion.

2. A hosiery inspecting device comprising a form, supporting means therefor, a pair of stretching fingers, means for yieldingly retaining said fingers normally inside the form, and means for moving said fingers to extend the outer ends thereof beyond the surface of the form.

3. A hosiery inspecting device comprising a form, supporting means therefor, a pair of stretching fingers pivotally mounted inside the form, and means for moving said fingers to extend the outer ends thereof beyond the surface of said form.

4. A hosiery inspecting device comprising a stocking receiving form having converging flat surfaces at one end, and stocking stretching fingers positioned to extend outwardly through the wall of said form in opposite directions and substantially parallel with the planes of said surfaces.

5. A hosiery inspecting device comprising a form, a supporting bracket therefor, a stretcher mounted in said form and having a portion adapted to be moved outwardly therefrom into stretching position, means for rotating said form relatively to said bracket, and means cooperating with said rotating means to move said stretcher into stretching position.

6. A hosiery inspecting device comprising a form having an elongated body portion of substantially circular cross sectional contour and a wedge shaped forward end portion having its lateral and end surfaces intersecting to form corners positioned and adapted to engage and extend corner stitches of the toe portion of a stocking to reveal knitting or looping faults therein.

7. A hosiery inspecting device comprising a form, supporting means therefor, a pair of stretching fingers normally positioned inside the form, and means for moving said fingers to extend the outer ends thereof in opposite

directions beyond the outer surface of said form.

8. A hosiery inspecting device comprising a form, supporting means therefor, a pair of stretching fingers, means for yieldingly retaining said fingers normally in retracted position, and means for moving said fingers to extend the outer ends thereof in opposite directions beyond the surface of the form.

9. A hosiery inspecting device comprising a stocking receiving form having converging flattened surfaces at one end, stretching fingers, and finger extending means, said fingers being so mounted and positioned in said form that when actuated by said extending means and with a stocking operatively positioned on the form, outer portions of said fingers move into stretching engagement with corner stitches of the toe seam of said stocking.

In testimony whereof, I have signed my name to this specification this 29th day of June, 1927.
